UNITED STATES PATENT OFFICE.

OSCAR C. RIXSON, OF CHICAGO, ILLINOIS, ASSIGNOR TO THE OSCAR C. RIXSON CO., OF CHICAGO, ILLINOIS, A CORPORATION OF ILLINOIS.

DOOR-CLOSING DEVICE.

SPECIFICATION forming part of Letters Patent No. 766,386, dated August 2, 1904.

Application filed May 21, 1900. Serial No. 17,386. (No model.)

To all whom it may concern:

Be it known that I, OSCAR C. RIXSON, a citizen of the United States, and a resident of Chicago, in the county of Cook and State of

5 Illinois, have invented certain new and useful Improvements in Door-Closing Devices, of which the following, taken in connection with the accompanying drawings, is a specification.

The first of the objects of my invention is 10 the provision of a door closing device which will be of strong and simple construction, reliable and efficient in its operation, and at the same time light in weight and cheap to manufacture. The several advantages enumerated

15 I secure by constructing my apparatus with two pivotally connected movable arms, one attached to the door and the other to the frame, and combining therewith an actuating spring, preferably of a cylindrical type, that 20 is, one designed to operate in what might be called a straight-line direction, as contradistinguished from a torsion spring, the spring being preferably carried by the arms and provided with connections whereby to normally 25 resist the rotative movement of the two arms relative to each other in the opening of the door.

Another means provided by me for accomplishing the several results above enumerated 30 consists in the provision of a bracket containing a liquid checking device, in combination with a spring, which is arranged in a casing, separate from the casing of the checking device, which is formed by the said bracket. 35 By this means, viz: having the spring casing a structure entirely separate and distinct from the bracket containing the checking device, I am enabled, by a mere inversion of the position of the spring casing, together with the 40 pivotally connected arms, to reverse the operation of the device without disturbing any of the parts of the checking mechanism, or the main bracket itself.

In carrying out my invention, the two pivotally connected movable arms above referred 45 to are arranged with their connections to the door and to the frame, respectively, also pivotal or rotative, and means are provided whereby the straight-line spring used by me

is caused to operate upon the said arms to 50 move the same by exerting force upon a point eccentric to one of the said pivotal connections.

In the preferred form of my invention, I also provide my apparatus with a bracket containing a checking device, and an arm pivoted to the bracket and connected with, so as to actuate the checking device, a spring being carried by the arm and so connected with the bracket and arm respectively as to exert a 60 force tending to resist the rotation of the arm upon the bracket.

A further object of my invention is the provision of a door check of improved construction, provided with an arm carrying a spring, 65 preferably within the arm, and means for reversing the position of the arm together with the spring, whereby the device may be made to operate either right or left.

Another feature of my invention relates to 70 the arrangement of devices employed to hold the spring arm in position upon the bracket casting, the arrangement being such as will obviate all danger of putting the parts together in a manner the reverse of what they 75 should be.

Another object of my invention is the construction of a door check containing a main casting having a cored cylinder therein, a lining within said cylinder, and means for 80 holding the said lining in position. Other door checks with which I am familiar have been heretofore constructed having checking pistons operating within cylinders turned within a main or bracket casting. I have 85 found from experiment and practice, however, that the fluids commonly used in such checking devices act deleteriously upon the cast metal of which such main or bracket casting is formed, causing a roughening or eating 90 away of the smooth surface of the cylinder, consequent leakage past the piston, and ultimately spoiling the checking fluid itself. By the provision of a lining inserted within a cored cylinder and arranged to permit the 95 checking piston to operate within such lining, I am enabled to make the casting of any desired material, and the bushing or lining of

some more suitable metal, as, for instance, pressed steel, which I have found to be very satisfactory for the purpose, while at the same time I eliminate the objectionable results mentioned as incidental to the prior practice.

In order to reduce the expense of manufacture and facilitate the repair of the device, I insert the lining from a lateral opening in the main casting or cored cylinder, and thus do away with all need of making the main casting with any openings at either end, or any caps for closing such openings. In order to accomplish this it is necessary that the cavity within the casting designed to receive the lining be cored out of a size somewhat larger than the outside of the lining itself, and that means be provided for holding the lining in position after it is put in the cavity.

Another object of my invention is the provision of novel means, to be hereinafter more particularly described, whereby the packing rings of the checking piston are held outwardly against the cylinder walls with a yielding force, and the openings between the several sections of the said rings are prevented from coming together and thus permitting leakage.

Another object of my invention is the provision of a door check comprising a bracket, an arm mounted thereon, a spring, means whereby the force of said spring is exerted against said bracket and arm respectively, a second arm having one end pivotally connected to the first arm, and mechanism at the other end of said second arm whereby the leverage of the device, with the door near closed position, may be substantially varied, as set forth, and without forming an increased resistance to be overcome through the balance of the range of movement of the door.

The above, as well as such other objects as may hereinafter appear, I obtain by means of a construction which I have illustrated in preferred form in the accompanying drawings, in which—

Fig. 1 is a side elevation of a door closing device embodying my invention;

Fig. 2 is a sectional plan view thereof;

Fig. 3 is a sectional view showing the connection whereby the spring operates to move the arm;

Fig. 4 is a vertical section through the bracket casting showing the checking plunger and its connection;

Fig. 5 is a sectional view of the plunger showing the valve therein;

Fig. 6 is a perspective view of the plunger packing rings;

Fig. 7 is a perspective view of the two rings separated a slight distance;

Fig. 8 is a perspective view of the spring device which I employ for holding the rings outwardly in contact with the cylinder walls and also preventing the meeting ends of the two adjacent rings from coming together.

Figure 9 represents a modification in which a folded flat spring 16 within the casing or arm 12 is used in order to actuate the chain 13, instead of the longitudinal spring shown in Figure 2.

Projecting upwardly from a bracket, 1, is a shaft, 2, journaled in a sleeve, 3, which is tightly secured in a cap, 4, which in turn is securely held against rotation, relative to the bracket, by the head of a screw, 5. An arm, 6, is pivotally mounted with one end surrounding the shaft and sleeve and arranged to have a rotative movement relative to the sleeve, but constructed to rotate the shaft with it, this action being secured by means of a second cap, 7, which has recesses, 8, of unequal size, designed to engage corresponding projections, 9, on the arm. The recesses and projections, together with a bolt, 10, which passes through the cap 7 and engages the shaft 2 on one side at 11, constitute interlocking features which, by virtue of their irregularity, as shown, make it impossible for even a careless workman to put the parts together wrongly when the device is first set up or when it is changed to reverse its operation.

The arm 6 is preferably tubular, and constitutes a casing or holding device within which is disposed a spring, 12, which acts against a chain or equivalent connection, 13, attached to a hook, 14, arranged to engage a groove, 15, in the sleeve 3. Pivotally connected to the arm 6, and movable relative thereto, I provide a second arm, 16, the end of which, opposite to its point of connection to the arm 6, is secured to the door or frame, as circumstances may require, by means of an adjusting device comprising an anchor block, 17, a movable socket, 18, and a screw, 19; operating in a manner which I shall now describe.

With apparatus of this class, as heretofore constructed, it has been necessary to exercise extreme care in securing exactly the right location of the anchor block to which the inner end of the second arm 16 is secured, as a variation of but a very small fraction of an inch in the position of this makes a material variation in the force or power exercised by the spring. In prior constructions it has also been impossible after the anchor block was secured, to adjust it, so as to get any variation in the strength or power of the spring, without taking it off entirely and putting it in a new position. This obviously cannot be done with any degree of accuracy. In my construction, by the arrangement of a small screw, I am enabled to move or adjust the socket to any desired position with the greatest ease and perfect accuracy and security. It is further to be noted that, by the arrangement just described, the different effect in the force and operation of the spring by suitable adjustment of the mechanism shown is substantial (in some cases over fifty per cent.)

and yet noticeable only when the door is nearly in closed position, which is just where it is desirable, as for example, to hold an unlatched door shut against the wind, or to close 5 the door against the resistance of the latch or friction of the casing.

After the door has been opened a few inches the effect of the adjustment materially decreases, and this continues until, when the 10 door is widely opened, the force necessary to move or hold it is equal to or even a little less than it was when the leverage of the spring with the door closed was at its minimum, because of the fact that moving the anchored 15 end of the second arm nearer the center of rotation of the first arm necessarily makes a slight change in the position of the first arm in direction to slacken the tension of the spring, although at the same time it increases 20 the leverage through which the spring acts so as to produce for the first few inches of door-opening a much larger degree of movement of the outer end of the arm.

So far as relates to the broad idea of my invention, it is obviously immaterial whether 25 the spring connection is such as to secure compression of the spring by winding the connecting member around a fixed sleeve, as shown in the drawings, or by holding the 30 spring relatively stationary and rotating the part to which the connecting member is attached, to effect a pull upon the said connecting member, as the latter would be but a mere reversal.

35 Within the bracket casting 1 is a cored cylindrical chamber provided with a pressed steel lining, 20, closed at one end, as at 21, and held in place either by a plurality of screws like the screw 22, or by pouring soft metal in 40 between the lining and the surrounding cylinder. Within the lining 20 is disposed a checking piston or plunger, 23, connected by a link, 24, to a crank arm, 25, secured upon the lower end of the shaft 2. A small port, 45 26, is provided in the lining 20, controlled by a valve, 27, and communicating with a passage, 28, through which, in the checking operation of the device, the checking fluid may 50 pass to the opposite side of the checking piston in the usual manner. The checking piston 23 is provided with a port, 29, through it, closed by a ball valve, 30, arranged as shown in Fig. 5.

The packing rings for the checking piston 55 are divided into halves, as shown in Figs. 6 and 7, and between the rings and the piston are disposed the spring devices, 31, having outwardly turned projections, 32, designed to engage the openings between the ends of the two 60 half rings, these two projections being so located on the spring 31 as to prevent the openings between the half rings of two adjacent rings from working around to the same point and causing leakage. The spring 31 itself is 65 made sufficiently wide to overlap back of both

rings, and the projection 32 upon one end of it is arranged to enter the opening between two adjacent portions of one ring, and the projection upon the other end of it is arranged to enter the opening between two adjacent 70 portions of the next ring. By making the spring less than the length of one-half of one of the rings, it is obvious that the various ring parts will be held in such position that they will break joints at different places, as shown 75 clearly at 33 and 34 in Fig. 6.

In order to cushion the checking fluid as the door is suddenly opened, I place an inverted channel or groove, 35, on the underside of the cap, as shown, whereby when the 80 checking fluid passes around to the adjacent side of the chamber, a small body of air will be confined within such inverted channel and form a cushion, which will yield slightly to the fluid and prevent a tendency to leak around 85 the shaft otherwise resulting from sudden and excessive augmentation of pressure at such point.

The operation of my invention is as follows: The parts being put together in the position 90 shown in the several figures and the chamber within the lining 20 filled with the checking fluid, as also the chamber upon the opposite side of the checking piston, when the door is opened the movement of the bracket 1 (because the outer end of the arm 6 is connected to the door frame through the instrumentality of the second arm 16) causes the arm 6 which carries the spring 12 to rotate in a direction to pull upon the chain 13 and compress the 100 spring, the hook 14 being fixed in the groove 15 formed in the sleeve 3. The arm 6 being made fast to the shaft 2 through the instrumentality of the projections 9, recesses 8, cap 7 and bolt 10, causes the shaft 2 to rotate with 105 it, and this, by means of the crank 25 and connection 24, imparts movement to the checking piston 23, the movement, while the door is opening, being in a direction away from the end wall 21 of the lining 20. During this 110 movement of the checking piston the checking fluid has free passage through the port 29 so as not to resist the opening of the door, but when the door begins to close the ball 30 closes the port 29 and the checking piston 115 then begins to exert pressure upon the checking fluid confined between it and the inner part of the lining 20, which is only relieved as the checking fluid is permitted to escape through the small port 26, past the adjusting 120 valve 27 and around to the opposite side of the chamber. The speed of the closing movement of the door may obviously be readily controlled by suitable adjustment of the valve 27.

In prior constructions of this class, where it has been possible to reverse their action at all, the change has involved considerable complication, because of the necessity of moving the springs and the arms separately and getting 125 130

them properly secured and connected in position. To change from right to left, or vice versa, with my construction, all that is necessary is to take out the small bolt 10, take off 5 the arm 6 and replace it the other side up, and then put the bolt back into place, taking pains, of course, to see that the hook 14 is properly caught in the notch 15.

What I claim as new, and desire to secure 10 by Letters Patent, is—

1. A door closing apparatus comprising a bracket casting, a shaft projecting therefrom, a sleeve surrounding said shaft, a movable arm mounted with one of its ends engaging 15 said sleeve and shaft, a spring within said arm, connections between said spring and said sleeve, and means for connecting the outer end of said arm with some part of the frame adjacent to the door.

2. The combination with the movable arm of a door closing apparatus, of a cap for holding said arm in place, sockets in the arm of different sizes, and lugs on said cap of sizes 20 to correspond with the sizes of the sockets, 25 and engaging therewith.

3. A door checking and closing apparatus comprising a bracket casting, a checking device within the same, a shaft projecting from said casting and constructed to actuate said 30 checking device, an arm mounted upon said shaft, a spring within said arm connected so as to resist movement of the same relative to said shaft, and means for reversing the position of said arm and spring, whereby the 35 spring and checking device may both be made to operate either right or left.

4. A door closing apparatus comprising a bracket casting, an arm and a spring carried by said arm, said arm and spring being 40 reversible in position relative to the bracket casting so as to operate either a right or left hand door, substantially as described.

5. A door closing apparatus comprising a bracket casting, a shaft projecting therefrom, 45 a movable arm mounted with one of its ends engaging said shaft, a spring within said arm, connections between said spring and means on said bracket casting, and means for connecting the outer end of said arm with some 50 part of the frame adjacent to the door.

6. A piston packing having a plurality of rings made in parts, and a device engaging the parts of the said rings and holding them in position so as to break joints at different 55 places, substantially as described.

7. A door check comprising a bracket, a checking device contained therein, an arm mounted upon the bracket and connected with said checking device so as to actuate the same, 60 a spring carried by the arm, and means whereby the force of said spring is exerted against said bracket and arm respectively, substantially as described.

8. A door check comprising a bracket, a 65 checking device contained therein, an arm

detachably and reversibly pivoted to said bracket and connected with said checking device so as to actuate the same, and a spring connected with said bracket and arm respectively so as to normally resist the rotation of 70 the latter upon the former, substantially as described.

9. A door check comprising a bracket, a checking device contained therein, an arm mounted upon the bracket and connected with 75 said checking device so as to actuate the same, a spring carried by said arm, and a chain rigidly secured at one end to said bracket eccentric to the pivot of said arm and at its opposite end engaging said spring, substantially 80 as described.

10. The combination in a door closing device of a chamber containing a checking device, a rotative spindle projecting from said chamber and connected with the checking device, an arm containing a resisting spring pivoted upon said shaft and a second arm attached to a fixed portion of the door frame and to the first mentioned arm, substantially as described.

11. In a door closing device the combination with an operating arm attached to the door frame, of a swinging hollow arm containing a retractile spring and mounted pivotally at one end, and means by which the swinging 95 of said latter arm contracts the spring by the motion of the door.

12. In a door closing mechanism the combination with the pivoted arm carrying a compression spring and mounted on a spindle 100 and rotating therewith, a supporting casing carrying the spindle and also a stationary sleeve, a chain engaging the sleeve and said spring whereby the swinging of the arm compresses the spring, and means on the spindle 105 and contained in a separate chamber of the casing for checking by liquid flow the rotation of the said spindle and said pivoted arm, substantially as described.

13. In a door closer the combination of a 110 hollow arm containing a compression spring therein, a rotatable spindle carrying said arm, a stationary sleeve engaging the spring and supporting said spindle and a supporting casing for the sleeve, containing means for opposing the motions of said arm and spindle, whereby the spring in the hollow arm rotates the spindle and the means in the casing retards the said rotation, substantially described.

14. In door closing mechanism the combination with a fixed casing, of a swinging arm mounted upon a shaft pivoted in said casing, a fluid retarding device contained in said casing in a separate closed chamber and connected to said shaft, a spring on said swinging arm and a connection to the casing whereby the swinging of the arm compresses the said spring, and a connection from said arm to the door.

15. In a door closing device the combination of a fixed casing having a rotatable spindle mounted therein, a fixed sleeve surrounding said spindle, a swinging hollow arm carried on said spindle and provided with a compression spring, flexible means attached to said spring for winding upon said fixed sleeve on the spindle, and a liquid retarding device for the movement of said spindle mounted 10 within the said casing, substantially as described.
16. In a door closing device the combination with a swinging arm and means for returning it to normal position, a link attached 15 to said arm and to the door frame, said link being provided in its said attachment to the frame with a lateral adjustment to vary the angle between the normal position of the link and the first mentioned swinging arm.
17. In door closing mechanism the combination of a swinging arm adapted to be pivotally connected to the door, a spring mechanism for moving said arm, an operating link pivoted at one end to said arm at the outer 25 end thereof, and attached to the door frame, and a means of attachment comprising a bracket and a screw rod mounted therein, a collar on the screw rod pivoted to the end of the link, whereby said link is adjustable in 30 position toward and from the pivoted position of the spring actuated swinging arm.
18. In a door closing device the combination with a fixed bracket having a fixed sleeve thereon, of a hollow spring-casing containing
- a spring and pivoted upon said sleeve and a 35 chain attached to said spring and to the sleeve so as to wind upon the said sleeve as the arm swings about its pivot.
19. In a door closing device the combination of a hollow swinging arm, a fixed casing, 40 a rotatable spindle therein supporting said arm, a spring in said arm and means for compressing it by winding upon a fixed portion of the casing, and a separate chamber in the casing containing means for checking the rotation of the spindle of the said arm, substantially described.
20. In a door closing device a hollow bracket provided with a rotary spindle and a fixed sleeve projecting therefrom, a door closing 45 arm pivoted upon the fixed sleeve and means for opposing the opening of the door, and means connected to said spindle operated by the swinging arm to check the return of the door, substantially as described. 55
21. In a door closing device, a hollow bracket forming a checking fluid chamber provided with a by-pass and with a separate lining for the piston cylinder and closed by a screw plug provided with a packing chamber. 60

In testimony whereof I have hereunder signed my name in the presence of the two subscribed witnesses.

OSCAR C. RIXSON.
